(57) **CLAIM**

The ornamental design for a folding mirror with sliding door storage compartment, as shown and described.

DESCRIPTION

FIG. 1 is a top perspective view of a folding mirror with sliding door storage compartment in folded position, and showing a preferred embodiment of our new design;

FIG. 2 is a bottom perspective view thereof;

FIG. 3 is a front-end view thereof;

FIG. 4 is a top plan view thereof;

FIG. 5 is a left-side elevational view thereof; the right-side being a mirror image thereof;

FIG. 6 is a rear end view thereof;

FIG. 7 is a perspective view thereof, showing the mirror in an unfolded position; and,

FIG. 8 is a left-side elevational view showing the mirror in an unfolded position, the right side being a mirror image thereof.
